[57] **CLAIM**

The ornamental design for a surgical instrument handle, as shown and described.

DESCRIPTION

FIG. 1 is a perspective view showing my new design for a surgical instrument handle;

FIG. 2 is a side elevational view thereof;

FIG. 3 is a rear elevational view thereof;

FIG. 4 is a front elevational view thereof;

FIG. 5 is a cross-sectional view along lines 5—5 in FIG. 2.

FIG. 6 is a cross-sectional view taken along lines 6—6 in FIG. 5;

FIG. 7 is a cross-sectional view taken along lines 7—7 in FIG. 5.

The broken lines showing an end piece is for illustrative purposes only and forms no part of the claimed design.
